UNITED STATES PATENT OFFICE

96,630

DESIGN FOR A SURFACE TREATING DEVICE

Jesse H. Smith, Westfield, Mass.

Application February 19, 1935, Serial No. 55,499

Term of patent 7 years

To all whom it may concern:

Be it known that I, Jesse H. Smith, a citizen of the United States, residing at Westfield, in the county of Hampden and State of Massachusetts, have invented a new, original, and ornamental Design for a Surface Treating Device, of which the following is a specification, reference being had to the accompanying drawing, forming part thereof.

Fig. 1 is a side elevational view of a surface

treating device showing my new design, the opposite side of the device being substantially the same as the side shown; and

Fig. 2 is an inverted plan view of the device shown in Fig. 1.

I claim:

The ornamental design for a surface treating device, as shown and described.

JESSE H. SMITH.
